CLAIM

The ornamental design for a basketball goal, as shown and described.

DESCRIPTION

FIG. 1 is a perspective view of a basketball goal showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof, the opposite side is a mirror image thereof;

FIG. 7 is a perspective view of an alternate embodiment of the basketball goal;

FIG. 8 is a front elevational view of the FIG. 7 illustration;

FIG. 9 is a rear elevational view of the FIG. 7 illustration;

FIG. 10 is a top plan view of the FIG. 7 illustration;

FIG. 11 is a bottom plan view of the FIG. 7 illustration; and,

FIG. 12 is a side elevational view of FIG. 7, the opposite is a mirror image thereof.
